UNITED STATES PATENT OFFICE.

PAUL RISSMANN, OF DETROIT, MICHIGAN, ASSIGNOR TO FISHER BODY CORPORATION, OF DETROIT, MICHIGAN, A CORPORATION OF NEW YORK.

MACHINE FOR THE MANUFACTURE OF CLOTH COVERING TUBES FOR AUTOMOBILE WINDOW SASH.

Application filed August 12, 1920. Serial No. 403,043.

To all whom it may concern:

Be it known that I, PAUL RISSMANN, a citizen of the United States, residing at Detroit, in the county of Wayne, and State of Michigan, have invented certain new and useful Improvements in a Machine for the Manufacture of Cloth Covering Tubes for Automobile Window Sash, of which the following is a specification.

10 This invention relates specifically to a machine for forming the covering for metal channels used to form the sash of an automobile closed body window. Of course, the invention is of broader scope than the manufacture of the specific material referred to. The broad invention may be said to be apparatus for making a piece of fabric tubing out of material folded upon itself and then secured together with an adhesive strip and 20 further in a broad sense the butt-joining of two pieces of fabric. The particular features of the construction will be best understood when a detailed description is had of the apparatus.

25 In the drawings,—

Fig. 1 is a side elevation of the machine.

Fig. 2 is a plan view of the machine.

Fig. 3 is an end elevation of the same taken from the right of Fig. 1.

30 Fig. 4 is a section on the line 4—4 of Fig. 2.

Fig. 5 is a section on the line 5—5 of Fig. 2.

Fig. 6 is a section on the line 6—6 of Fig. 2.

One of the most common forms of window sash now used for automobile closed bodies is one that is formed by a metal channel and suitably covered usually with a felt 40 cloth or equivalent fabric material (see patent to John T. Allmand No. 1,147,837). The present method of fastening this cloth to the channel strip is to form it into a tube of proper width, whip-stitching it together.

45 This forms a tube into which the channel may be slid, together with the packing that has been glued to it (see patent to A. Gagnon No. 1,243,728, for description of how the felt packing can be applied). This packing

50 is covered with glue or other adhesive before being slid into the fabric tube. A form member is then slipped into the channel pressing the fabric into the bottom of the channel and tightening the fabric on the

sides. This is left to stand until the glue 55 hardens and then the form is removed and the glass slid into the channel. The stitching of the fabric to make the tubing has heretofore been a hand operation to the extent that the operator must guide the material into the stitching machine (the sewing machine) and see that it is evenly fed and stitched. This is not only a slow and expensive operation compared with an automatic operation but the results are not as good for 60 the reason that the stitching cannot possibly be as regular as work done by the apparatus now about to be described.

a designates a bench on which a machine performing the work outlined is fastened. 70 The machine comprises a base b attached by bolts c to the table a. e is a pulley wheel adapted to be driven by a belt and having a shaft f journaled in the bearing g rising from the base b. The spool h stores a 75 roll of fabric ribbon while a narrower spool i stores a roll of tape impregnated with rubber or some other sticky or glue-like substance. This will be called an adhesive tape in the claims. j is a guide arranged to take 80 a cloth or fabric ribbon, double it upon itself to form a strip or preliminary tube of half the width of the original fabric, with the meeting edges meeting at the center of the strip. This it accomplishes by the folded-over converging guide k shown in Fig. 2, and sections of which are shown in Figs. 4 and 5. Suspended above the cloth and supported upon this guide j, is a centering guide l for the adhesive tape l. This centering 85 guide m simply rests on the top n of the fabric ribbon guide, being soldered to the reinforcing strip o soldered to this top. Another centering guide for the adhesive tape is designated p and is also soldered to the 90 top of the fabric ribbon guide where it turns the outside in. This guide may now be properly appreciated. The fabric is fed off from the spool flatwise into this guide. By examining Fig. 4, it will be seen that the 95 guide almost immediately begins to turn the edge portions of the ribbon in or concave the ribbon. The edges of the guide then are completely turned over (the outside turns in) at k until they meet. A little partition q 100 divides the turned-over edge portions of the ribbon, while the top n (that has been turned from outside in) serves to divide the folded-

over portions of the strip from the main web.

The preliminarily-formed tube *r* then passes over the heating iron or surface *s* and 5 then around the reversing roll *t*, which serves to reverse the surface of the strip that is fed upon the heating roll *u*. This heating roll *u* has a hollow interior in which is suspended a ring *v* having gas jet orifices 10 which form a burner for heating the interior of the heating roll *u*. This member is suspended within the roll by the pipe *w* which supplies the mixture for combustion. It will be evident from this description that 15 first the under side of the preliminarily-prepared fabric tube is heated by being drawn over the concave heating iron *s*. This heating is only an indirect or secondary one as only heat first used on the heating roll *u* 20 reaches the concave iron *s*. This is all that is required to warm the preliminarily-formed tube on the under side. The preliminarily-formed tube is then reversed by the roll *t*, and the side that has the meeting 25 edges which are desired to be secured to the rubber-impregnated tape is brought directly over the relatively higher heated heating roll *u*. The rubber in the tape is thus caused to melt and soften. The heating roll then 30 pinches the preliminarily-formed tube between itself and the pressure roll *x*. This forces some of the softened fluid-like rubber compound into the edge portions of the fabric where they meet, thereby securely fastening the fabric edges to the impregnated 35 tape and thereby firmly securing them to each other. The completed fabric tubing then passes on to the spool *y*, completing the same and making it ready for use.

40 The heating roll is carried on a shaft *z* which is journaled in a yoke or support 1. The pressure roll *x* is always fixed and always rotating, being carried on the end of the pulley shaft *f*. As soon as the heating 45 roll *u* is pressed against the pressure roll *x* it starts the tape, fabric ribbon, and the completed tube moving in this way: the heating roll *u* being pressed against the pressure roll *x* that is rotating, is also caused to rotate.

50 This pulls the reversing roll *t* from the position shown in the dotted lines of Fig. 6 over against the heating roll, as shown in full lines in this figure. The ironing roll then serves to rotate the tape spool and the fabric ribbon spool simply by pulling the material off from these two spools. The shaft *z* is journaled in the yoke 1, which is pivotally supported on the upstanding lugs 2 of the casting which forms the base *b* of the 55 machine. Within the space between the yoke legs is located a pulley wheel 3 fast to the shaft *z*. This, through a belt or cord 4, drives the pulley wheel 5, which in turn drives the storage spool *y*. The belt may 60 slip enough to compensate for an otherwise 65

differential peripheral speed of the spool *y* as it fills up.

As already indicated, the yoke 1, which journals the heating roll and is pivoted to the base at 6, may be drawn down to bring 70 the heating roll against the pressure roll *x*. The foot of the operator may be brought against the pedal 7 which connects through the draw rod 8 with the yoke 9 that has two arms 10 connected with opposite sides of the 75 yoke.

Referring to Fig. 3, it will also be seen that the lugs 11 on the bed casting support an arm 12 which supports the guide *j*.

One side of the spools *i* and *h* may be 80 slipped off at any time to replace the tape or fabric ribbon by loosening the set screws 13 and 14.

It will be apparent that in a broader sense the apparatus is a machine for joining in a 85 butt-seam two pieces of fabric, and hence claims are directed to this.

What I claim is:

1. A machine for butt-joining fabric portions, comprising a guide having the capacity of directing and guiding the edges of the fabric portions to hold the same in abutting relation and also to guide an adhesive tape along the meeting edges, a heater, a pressure member, and means for directing 90 and pulling the fabric and tape in adjacency to the heater and into the pressure member, which serves to force the adhesive tape upon the said adjoining edges of the fabric.

100

2. A machine for butt-joining fabric portions, having in combination, a guide for directing fabric pieces into abutment at their edges and also serving to guide a traveling adhesive tape upon the edge portions abutting, a heater, a pressure member, and means for pulling the tape and fabric in proximity to the heater and against the pressure member to press the adhesive tape against the edge portions of the fabric to 105 complete the same.

110

3. A machine for butt-joining fabric portions, having in combination, a guide for directing the edge portions of traveling fabric into abutting relation and at the 115 same time guide a traveling adhesive tape alongside of the edge portions, a heating roll, a pressure roll, and means for drawing the fabric and adhesive tape over the heating roll and between the pressure roll and the member against which it presses.

120

4. A machine for butt-joining fabric edges, comprising a guide for directing the edges of traveling fabric to cause them to abut and at the same time direct a traveling adhesive tape alongside of the edges, a heating roll journaled in a movably-hung support, a pressure roll against which the heating roll abuts, and means for drawing the fabric and adhesive tape over the heating 125 130

roll and between the pressure roll and the heating roll.

5. A machine for butt-joining fabric edges, having in combination, a guide for directing the edge portions of traveling fabric to cause them to abut and also for guiding a traveling adhesive tape along the edge portions of fabric, a heating roll journaled in a pivotally-hung support, a pressure roll, means by which the operator may move the pivotal support for the heating roll to press the same against the pressure roll, and means for pulling the fabric and tape over the heating roll and between the heating roll and pressure roll.

6. A machine for butt-joining fabric edges, having in combination, a guide for directing fabric portions to cause the edges to abut and at the same time guiding a traveling adhesive tape alongside of the meeting edges, a heating iron, a heating roll having a greater heat than the first-mentioned heating iron, means for reversing the traveling fabric and tape that pass from the heating iron to the heating roll, means for pressing

the tape and fabric edge portions together after having passed over the heating roll, and means for pulling the fabric and tape through the aforementioned instrumentalities.

30

7. A machine for butt-joining fabric edges, having in combination, a guide for directing traveling fabric to cause the edge portion to meet and at the same time guiding a traveling adhesive tape alongside of the edge portions, and a heating roll and heating iron above the heating roll, means for heating the ironing roll and giving the heating iron a secondary heat, a reversing member for taking the fabric and tape as it leaves the heating iron and reversing the same as it passes on to the heating roll, means for pressing the adhesive tape to the fabric edge portions as it passes off the heating roll, and means for drawing the tape and fabric through the aforementioned instrumentalities.

In testimony whereof I affix my signature.

PAUL RISSMANN.
